(57) **CLAIM**

The ornamental design for a dental wedge, as shown and described.

DESCRIPTION

FIG. 1 is a perspective view of a dental wedge embodying the new design;

FIG. 2 is a top view thereof;

FIG. 3 is a front view thereof;

FIG. 4 is a rear view thereof;

FIG. 5 is a right view thereof; and,

FIG. 6 is a left view thereof.

The broken lines shown in the figures depict portions of the dental wedge that form no part of the claimed design.

1 Claim, 3 Drawing Sheets
